UNITED STATES PATENT OFFICE.

NORMAN C. RENDLEMAN, OF DORMONT, PENNSYLVANIA, ASSIGNOR TO JONES & LAUGHLIN STEEL CORPORATION, OF PITTSBURGH, PENNSYLVANIA, A CORPORATION OF PENNSYLVANIA.

METAL ROLLING.

Application filed June 20, 1922. Serial No. 569,730.

To all whom it may concern:

Be it known that NORMAN C. RENDLEMAN, a citizen of the United States, and resident of Dormont, in the county of Allegheny and State of Pennsylvania, has invented an Improvement in Metal Rolling, of which the following description, in connection with the accompanying drawings, is a specification, like characters on the drawings representing like parts.

This invention aims to produce flanged structural members, such as I-beams and channels, of light weight and great depth in proportion to the web thickness, particularly such as are suitable for replacing wood beams and so-called "metal lumber" for building and other purposes, but it is not restricted to these uses.

In the accompanying drawings, wherein I have shown one embodiment of the invention for purposes of illustration,

Fig. 1 is an end view of an I-beam having characteristic features of my invention;

Fig. 2 is a cross-section of a suitable beam blank for producing the I-beam shown in Fig. 1;

Figs. 3 and 4 are views of typical shapes of roll passes for thinning the web and increasing the depth of the blank shown in Fig. 2, the resulting cross-sectional shape being shown in each view.

Fig. 5 is a view of a closed pass for elongating and shaping the I-beam as shown in Fig. 1;

Fig. 6 is a diagram illustrating the successive stages of rolling for comparison; and

Fig. 7 is a view of another arrangement of rolls for giving the beam its finished shape.

Referring to Fig. 1, the I-beam 10 therein shown has a depth of approximately three times the breadth of its flanges 11, and the web 12 is approximately one-sixty-fourth of its depth, which is very much thinner than has heretofore been considered possible in proportion to the depth. The shape and relative proportions give the beam much greater strength, in proportion to its weight, to carry transverse loads than I-beams of the same weights as heretofore rolled.

The improved product may be rolled from a billet or bloom by my improved method,

or it may advantageously be produced from a suitable blank of dimensions and proportions easily obtained by ordinary rolling operations, such as the blank 13 shown in Fig. 2, wherein the breadth and depth are nearly equal and the thickness of the web is about the same as that of the flanges where they join the web. Such a blank may be rolled from a suitable billet at one heat.

Preferably the blank 13 is of such dimensions as to have about the same or slightly greater cross-sectional area in web and flanges as the finished I-beam 10, and the weight per foot of the blank is preferably not much in excess of the weight per foot of the finished beam. For example, a 3" standard I-beam weighing about 7½ pounds per foot may be rolled into a 7½" I-beam weighing about 7 pounds per foot with an elongation of about 15% in length, the increase in the depth from 3" to 7½" being 70 accompanied by a corresponding decrease in the thickness of the web with but little change in the dimensions of the flanges and relative cross-sectional areas of the web and flange. The increase in the strength and 75 stiffness of the beam due to its increased depth is such as to make it available for floor beams of a span length for which the 3" beam is not suitable.

Heretofore it has not been commercially practicable to roll shapes having the extreme proportions readily produced by my invention, and such shapes have been approximated only in built up structures such as by riveting, brazing or spot welding separate pieces together with attendant disadvantages.

As illustrated in Figs. 3 and 4 of the drawings, my invention contemplates thinning of the web 12 with resulting separation of the flanges 11 to increase the depth of the beam by passing the blank through a series of grooves 14, 15, formed in rolls which engage the web but are spaced away from the flanges to permit the latter to accommodate themselves freely to any change in the web. The rolls are preferably beveled or tapered at the ends of each groove, or slightly crowned on their faces, and the number of grooves may be increased to produce the extent of thinning and widening of the web desired. As the rolls do not 100 touch the flanges there is no reduction or 105

substantial increase in length of the flanges or of the blank, and the blank may advantageously be passed through the successive grooves in one continuous operation, thereby enabling it to be rolled at the same heat as it was formed from the billet.

Preferably the successive web thinning passes are designed to operate on the web starting at its median line and proceeding 10 toward the flanges, the thinning of a portion being completed at each pass to its final thickness, so that no substantial thinning of such completed portion is effected in succeeding passes prior to the finishing operation.

One or more final passes through rolls 16 having closed passes of usual shape, as shown in Fig. 5, or universal rolls, as shown in Fig. 7, may advantageously be added to 20 finish the beam. A portion of the thick metal left in the web near its junction with the flanges (see Fig. 4) may be rolled into the web in the finishing operation thereby increasing the depth of the beam.

25 The comparative dimensions of the blank in its successive stages of manufacture are depicted in Fig. 6 to illustrate the manner in which the beam may be widened without a substantial change in any of its other dimensions except the thickness of the web prior to the final finishing. Inspection of the beam in its various stages shows that the metal of the web flows away from the median line toward the flanges, thereby forcing the flanges apart, instead of flowing lengthwise of the beam with consequent elongation as in the ordinary process of rolling. This forcing of the flanges apart elongates them slightly with a resulting 35 slight elongation of the beam as a whole; but this elongation is distinguishable from that produced by rolling a beam in the ordinary manner, as it is accompanied by the lateral spreading of the web.

40 45 The invention obviously is not restricted to the particular embodiment thereof nor to the means for producing it herein illustrated and described.

Having described one illustrative embodiment of my invention, what I claim and desire to secure by Letters Patent is as follows:

1. Rolling flanged shapes having marginal flanges of greater width than the intervening web portion by displacing the metal of the web portion sidewise progressively from the middle without substantial elongation.

2. Rolling flanged shapes by displacing the metal of the web portion sidewise pro-

gressively from the middle without substantial elongation.

3. Rolling flanged shapes having marginal flanges of greater width than the intervening web portion by displacing the metal of the web portion sidewise without substantial elongation.

4. Rolling flanged shapes by passing them through rolls having working faces acting upon the web portion and nonworking 7 grooves to straddle the flanges.

5. Rolling flanged shapes by using a series of passes having working faces acting upon the web portion and nonworking grooves to straddle the flanges, the grooves of succeeding 7 passes being spaced farther apart than those next preceding.

6. Rolling flanged shapes by passing them at substantially uniform speed through series of roll sets having grooves to straddle 8 the flanges, the grooves of succeeding sets being spaced farther apart than those next preceding whereby the shape is widened with minimum elongation.

7. The process of rolling a thin web shape 8 from a normal flanged shape which comprises the use of a series of passes of increasing width of face, the roll faces of each pass being spaced apart substantially equal amounts at their middles and having grooves 9 at their ends straddling the flanges.

8. The process of rolling a thin web shape 9 from a normal flanged shape which comprises the use of a series of passes of increasing width of face, the roll faces of each pass being tapered towards the ends and spaced apart substantially equal amounts at their middles and having grooves at their ends straddling the flanges.

9. The process of rolling a thin web shape 10 from a body of given length which comprises the use of a series of passes to progressively thin the body by lateral flow substantially without lengthwise extension.

10. The process of rolling a thin web 11 shape from a flanged blank which comprises thinning and widening the web progressively from the median line of the blank toward the flanges in a series of roll grooves of increasing width.

11. The process of rolling a thin web shape from a flanged blank which comprises thinning and widening the web progressively from the median line of the blank toward the flanges in a series of roll grooves 11 of increasing width operating simultaneously upon successive portions of the shape.

In testimony whereof, I have signed my name to this specification.

NORMAN C. RENDLEMAN.
